UNITED STATES PATENT OFFICE

JOHN WILSON BROWN, JR., OF PHILADELPHIA, PENNSYLVANIA

BOSSED ARM DRILLING MACHINE

Application filed November 8, 1930. Serial No. 494,432.

This invention relates to drilling machines, and more particularly to a multiple spindle machine for drilling bossed arms.

An important object of the invention is the provision in a device of this character of an assemblage such that the drilling may be conveniently carried out during rotation of the work about a central axis about which the drilling spindles are bodily rotated.

10 A further object of the invention is the provision of an assemblage of this character which while particularly adapted for use in the drilling of bossed arms may be conveniently employed in drilling or finishing other articles.

15 A still further object of the invention is the provision in an apparatus of this character of means for cooling the drilling tools and for taking care of the cuttings and coolant in their discharge from the machine.

20 A still further object of the invention is the provision of a novel and improved aligning means for use in machines of this character which is particularly adapted for use therewith.

25 A still further object of the invention is the provision of a novel and improved means for securing and maintaining proper alignment between the drilling tool and the work table.

30 These and other objects I attain by the construction shown in the accompanying drawings wherein, for the purpose of illustration, I have shown a preferred embodiment of my invention and wherein:

Fig. 1 is a perspective view of a multiple spindle machine embodying my invention;

Fig. 2 is a vertical sectional view therethrough, portions of the mechanism being removed;

Fig. 3 is a sectional view illustrating the work-holding mechanism in plan;

Fig. 4 is a front elevation thereof; and

Fig. 5 is a perspective view showing the type of arm for which the work-holding mechanism illustrated is particularly adapted.

Referring now more particularly to the drawings, the numeral 10 generally designates a base, from which arises a standard 11

which is reduced adjacent its lower end at 12 and again at 13 and at its upper end bears a head 14 supporting a transversely-extending drive shaft 15. Surrounding the reduced portion 12 is a cam support 16 which has a sliding fit over the lower end of the base and is keyed thereto at 17 to prevent relative rotation. Near its upper end, the inner face of the cam support has an inwardly-extending flange 18 slidably fitting the reduced portion 12, which portion is threaded externally as at 19 and mounts an adjustable bearing ring 20, adjustment of which is effected through a worm 21 mounted in the cam support and co-acting with worm threads 22 upon the outer face of the bearing ring. At the upper end of the support the control cam 23, for mechanism hereinafter described, is mounted, this cam serving to maintain in position upon a flanged lip 24 at the upper end of the cam support a trough 25 for the reception of coolant and cuttings in a manner hereinafter described. The outer edge of this trough serves to support a guard rail 26 which, for a purpose hereinafter more fully set forth, is interrupted at one point in its circumference.

Surrounding the reduced portion 13 of the carrier and seated upon a step bearing 27 mounted on the shoulder 28 produced at the junction of the portions 12 and 13 is a carrier generally designated at 29. The lower portion of this carrier has secured thereto a slide carrier 30 keyed to the carrier 29 as at 31 to prevent relative rotation therebetween. This slide carrier has a sloping upper face 32 and has formed in the side wall thereof a series of circumferentially-shaped pockets 33, the bottom walls of which likewise slope downwardly and outwardly so that any liquids or solids falling upon either the upper surface of the slide carrier or upon the bottom wall of the pocket will tend to move outwardly and downwardly, finally coming to rest in the trough 25.

The slide carrier mounts a sweep brush 34 operating in the trough so that as the carrier 29 is rotated carrying with it the slide car-

100

rier, the brush acts to sweep all materials delivered to the trough longitudinally thereof and thus through a discharge opening 35. The slide carrier, above and below each 5 pocket 33, has guide bearings 36 slidably receiving the upper and lower sections 37 and 38 of a two-part slide, the sections of which are held against rotation in the bearings as by means of keys 39 and are connected to 10 one another by a turnbuckle screw 40 so that the effective length of the slide may be regulated. The upper section 37 is formed with a table 41 while the lower section thereof provides a cam-engaging element at 15 present shown as a roller 42 seating upon the upper surface of the cam 23.

The upper end of the carrier 29 is defined by vertically-spaced outstanding flanges 43 and 44 preferably reinforced in alignment 20 with the slides by radial webs 45 connecting the same. In alignment with each slide the flanges are provided with aligned bores for the passage of spindles 46 each of which is mounted at its lower end in the flange 44 through a radial bearing 47 and a thrust 48 and has at its upper end a radial bearing 49 slidably mounted in the opening of the flange 43 and urged upwardly by a spring 50. This structure serves to remove any 25 play which may occur through wear at the thrust 48.

The upper surface of flange 43 has secured thereto a bevel gear 51 and disposed outwardly of this bevel gear a composite gear 35 52 is rotatably mounted about gear 51 and upon the upper surface of the flange. The upper surface of the composite gear is formed as a bevel gear 53 while the outer surface thereof is provided with teeth 54 40 meshing with pinions 55 secured to the upper ends of the spindles 46. The base portion of gear 51 constitutes a compound bearing element 56, the outer face of which forms one race of a radial bearing, and the 45 inner surface of which has a step 57 forming a race of a thrust bearing, the complementary race 58 of which is carried by the head 14 and is adjustable through screws 59 extending vertically through the head and 50 engaging the upper surface thereof. Adjustment of the race 58 removes any tendency to vertical play on the part of carrier 29 and since the thrust face of the race 58 is tapered, likewise serves to maintain the 55 upper end of the carrier 29 in proper concentricity to the standard 11.

The head 14, in addition to shaft 15 hereinbefore mentioned, mounts shafts 60 and 61 which are driven at different and suitably 60 selected speeds from the shaft 15. Shaft 60 has a pinion 62 meshing with gear 51, while shaft 61 has a pinion 63 meshing with the element 53 of the compound gear 52. It will be obvious that when shaft 15 is driven the 65 carrier 29 will be rotated about standard 11

and at the same time gear 52 will be driven at a different speed so that it moves upon the carrier and thus transmits rotation through pinions 55 to the spindles 46. Rotation of the carrier through cam 23 will result in rise 70 and fall of the slides of slide guide 30 so that the heads 41 will approach and recede from the spindles as the carrier is rotated. Through adjustment as by regulation of the cam, the extent of the reciprocatory motion 75 imparted to the slides may be very closely regulated and by adjustment of the slides themselves the space between a spindle and the associated head and, accordingly, the space between the piece of work carried by 80 the head and a tool carried by the spindle may be closely determined so that at the time when these elements have their greatest spacing a minimum workable clearance 85 may be maintained.

The outer ends of the pockets 33 of the spindle carrier are preferably closed by hinged doors 64 and the guard rail 26 is 90 preferably provided with doors 65 corresponding to the stations through which access may be had to slides so that with the machine stopped, an adjustment of all of the slides may be effected.

Mounted upon each head 41 is a table 66 having its under surface recessed as at 67. 95 The upper surface of the table has a socket 68 within which is seated a cup 69. This cup comprises a base 70 from which arise a series of circumferentially-spaced projections 71 adjacent faces 72 of which are inclined downwardly so that a downwardly tapering socket is defined thereby, the walls of which have slots 73. Slidably directed through the table is a headed stud 74 urged downwardly through the table by a spring 75. Surrounding this stud is a sleeve 76 reduced at its upper end to provide a seat 77. Between the upper extremity of the bushing and the head 78 of the stud a washer 100 is arranged, this washer having a convex lower face 79. Arising from the table adjacent the rear end thereof are a pair of guide rods 80.

Arranged above each table is a plate 81 115 which is secured to the lower ends of guide rods 82 and 83, the upper ends of which are passed through, and slidably in, bearings formed in flanges 43 and 44. The guide rod 82 has adjustably mounted thereon a stop nut 84 which, seating upon the upper surface of the flange 44, limits downward movement of the guide rod 82 and, accordingly, downward movement of the plate 81. Between the stop nut 84 and the flange 43 a spring 120 85 surrounds the rod 82 and serves to constantly urge this rod downwardly so that the nut 84 would normally engage flange 44. Secured to the lower surface of the plate 81 125 is a cup of the same type as the cup of table 130

66. Plate 81 has openings through which the guide rods 80 extend.

It will be obvious that in adjusting the tables 66 upon the heads, engagement of these guide rods in the openings of the plate 81, before tightening of the clamp bolts 86 securing the table in position upon the head, will insure proper alignment between these elements. Plate 81 may embody a drill 10 guide 87 to guide a drill 88 carried by spindle 46 and may have secured thereto an element 89 of a coolant delivery pipe 90, communicating at its upper end with a stationary coolant trough 91 in the manner described in my prior application filed March 15 14, 1930, Serial No. 435,893.

Apparatus of the character just described is particularly adapted for drilling double bossed arms such as exemplified by gear-shifting fork 92 illustrated in Fig. 5. This fork comprises an arm 93 having opposite faces thereof provided with aligned bosses 94 and having in one end a slot 95. The bosses of the arm have an outstanding rib 25 96 and in the completed structure a bore 97 extends through the bosses for the passage of a shaft upon which the fork is mounted. The operation performed by the machine is that of forming the bore 97 and in inserting 30 this arm to the machine which is done when the table 66 and the plate fixture 81 are most widely separated, one of the bosses is seated in the lower cup with the slot of the arm embracing the reduced portion of bushing 35 76 beneath washer 79. The downward pressure exerted by this washer upon the arm at the sides of the slot tends to hold the bossed portion of the arm upward while the cup 69 of the table centers this lower boss. 40 As the carrier rotates and cam 23 elevates the table 66, the upper boss engages in the cup of the plate 81 and is centered thereby, spring 85 providing sufficient pressure to insure maintenance of position. After the 45 upper boss is fully seated, the plate 81 moves upwardly with the table and the drill 88 comes into engagement with the work to form bore 97. It will be quite obvious that although the fixtures of the table and plate 50 81 are at present illustrated for use with the particular type of bossed arm shown in Fig. 5, a slight modification thereof would adapt the structure for use with any bossed arm whether it be double bosses as illustrated in this figure, or have a single boss and whether it be provided with a slotted arm or not. It is merely necessary that 55 means be provided for properly centering the work at both ends of the portion thereof 60 which is to be drilled and that a means be provided for guiding the work to the positioning means of the plate 81.

The structure being otherwise capable of modification without in any manner departing from the spirit of my invention, I do 65

not wish to be understood as limiting myself thereto except as hereinafter claimed.

I claim:

1. In apparatus for performing rotary cutting operations on bossed arms and in combination a cutter, a work table, means for relatively moving the cutter and work table to cause approach thereof, a cup carried by the work table to receive the boss of the arm, a yieldable member associated with the cutter to engage the arm and force the boss into the cup prior to engagement of the cutter with the arm, and means to yieldably engage the outer end of the arm in spaced relation to the cup and maintain the same in predetermined spaced relation to the work table. 70

2. In apparatus for performing rotary cutting operations on bossed arms and in combination a cutter, a work table, means for relatively moving the cutter and work table to cause approach thereof, a cup carried by the work table to receive the boss of the arm, a yieldable member associated with the cutter to engage the arm and force the boss into the cup prior to engagement of the cutter with the arm, and means upon the work table embodying resiliently engaged clamping elements adapted to receive the arm in spaced relation to the boss thereof. 75

3. In apparatus for performing a rotary cutting operation on a bossed arm having bosses at opposite faces thereof and in combination a cutter, a work table, means for relatively moving the cutter and work table to cause approach thereof, a cup carried by the work table to receive a boss at one side of the arm, a yieldable member associated with the cutter having a cup to receive the boss at the opposite face of the arm, and means carried by the work table in spaced relation to the cup thereof to engage the outer end of the arm and maintain the arm in predetermined relation to the work table, said means including yieldably engaged members between which the arm is clamped. 100

4. In apparatus for performing a rotary cutting operation on a bossed arm having bosses at opposite faces thereof and in combination, a cutter, a work table, means for relatively moving the cutter and work table to cause approach thereof, a cup carried by the work table to receive a boss at one side of the arm, a yieldable member associated with the cutter having a cup to receive the boss at the opposite face of the arm, and clamping means carried by the work table in spaced relation to the cup thereof to engage the outer end of the arm and maintain the arm in predetermined relation to the work table with the last-named boss positioned for entry in the cup of the yieldable member. 115

5. In a rotary cutting machine, a stationary standard, a carrier mounted for rota- 120

- tion, cutters, a plurality of tables carried by the carrier, movable slides mounting said tables, means for moving said slides to cause work carried by the tables to move into and out of cooperative relation with the cutters, including a stationary support carried by the standard, an annular trough fixed to said support and adapted to receive cuttings from cutters carried by said spindles, said trough having a discharged opening in its bottom and a brush carried by the carrier and operating in the trough to propel the cuttings along the trough bottom to said discharge opening.
- 15 6. In a rotary cutting machine, a stationary standard, a carrier mounted for rotation, cutters, a plurality of tables carried by the carrier, movable slides mounting said tables, means for moving said slides to cause work carried by the tables to move into and out of cooperative relation with the cutters, including a stationary support carried by the standard, an annular trough fixed to said support and adapted to receive cuttings from cutters carried by said spindles, said trough having a discharged opening in its bottom, a brush carried by the carrier and operating in the trough to propel the cuttings along the trough bottom to said discharge opening, and a guard rail mounted upon the outer edge of said trough.
